UNITED STATES PATENT OFFICE.

EDUARD VON OREL, OF VIENNA, AUSTRIA-HUNGARY, ASSIGNOR TO THE FIRM OF
CARL ZEISS, OF JENA, GERMANY.

STEREO-ISOHYPSONOGRAPH.

1,090,494.

Specification of Letters Patent. Patented Mar. 17, 1914.

Application filed December 13, 1911. Serial No. 665,574.

To all whom it may concern:

Be it known that I, EDUARD VON OREL, a citizen of Austria, residing at Vienna, Austria-Hungary, have invented a new and useful Stereo-Isograph, of which the following is a specification.

The object of the present invention is to enable a single person to derive by mechanical means from a stereoscopic pair of photographs of a landscape a plan or map of the said landscape, principally in the form of a system of contour-lines (isohypsal lines), or particular points in the said landscape.

The new apparatus, which serves this purpose, is a combination of a stereo-comparator, a drawing device and a system of actuating devices, the said system being accessible to the operator while looking into the stereo-comparator. These three principal parts are positively connected with each other in such a manner that the position of the pencil-point on the surface of the drawing always corresponds to that point in the landscape which is indicated in the stereo-comparator.

A stereo-comparator is usually fitted with a double microscope, which is binocular or monocular and contains a mark in each of the two image-fields or in the common image-field respectively. An ordinary stereo-comparator comprises further three slides, a height-slide a breadth-slide and a depth-slide. The height-slide causes a relative displacement of the microscope and the photographs in the height-direction of the latter, the breadth-slide just such a displacement in the breadth-direction of the photographs, while the depth-slide alters the distance apart of the photographs.

A triple slide system may serve as the drawing device. One of these slides, which shall be called the tracer height-slide, must change its location in accordance with the position as to height, which the object-point to be plotted in the map occupies in the landscape. The other two slides are the tracer breadth-slide and the tracer depth-slide respectively. They move the pencil or the drawing surface in the breadth-direction and the depth-direction respectively. The tracer depth-slide is the carrier of both the tracer breadth-slide and the tracer height-slide. It is convenient to make the tracer breadth-slide the carrier of the pencil, when the drawing surface has a fixed position.

Generally speaking the place of the plane drawing surface may be taken by one that can be developed into a plane, e. g. a cylindrical surface. For tracing isohypsal lines, two actuating devices controlling the apparatus in the breadth-direction and in the depth-direction respectively are sufficient for operating the apparatus, these actuating devices being adapted preferably to act on the drawing device.

The coupling between the stereo-comparator and the drawing device consists in a suitable positive connection of the three comparator slides on the one hand and of the three tracer slides on the other hand. When the two photographs are displaced by the comparator breadth-slide, the comparator depth-slide must be coupled with the tracer breadth-slide and the tracer depth-slide, and in such a manner that the distance apart of the photographs remains unaltered, when only the tracer breadth-slide, but not the tracer depth-slide as well, changes its locus. The coupling between the comparator depth-slide and the tracer depth-slide is intended to displace the pencil-point from the zero-depth-line (the copy, so to speak, of the vertical plane laid through the base-line determined by the objectives used in taking the photographs) by an amount, which is the product derived from the length of this base-line, the focal length of the said objectives, the scale of reduction of the copy and the reciprocal of the surplus, which the distance apart of the photographs, caused by the comparator depth-slide, shows, as compared with the minimum distance belonging to infinitely distant object-points (which indeed is never realized), this surplus being the so-called parallax.

The comparator height-slide is to be coupled with the tracer height-slide and the tracer depth-slide in such a manner that the tracer height-slide is displaced (negatively or positively) from its zero-position, by an amount, which is the product derived from the (negative or positive) displacement of the comparator height-slide out of the zero-position, the reciprocal of the focal length of the objectives and the distance of the pencil-point from the zero-depth-line, the latter distance being the product derived from the distance of the point in the landscape from the base-line and the scale of reduction of the copy.

The comparator breadth-slide is to be coupled with the tracer breadth-slide and the tracer depth-slide in such a manner that thereby the pencil-point is displaced (negatively or positively) from the zero-breadth-line by an amount, which is the product derived from the (negative or positive) displacement of the comparator breadth-slide out of the zero-position, the reciprocal of 10 the focal length of the objectives and the distance of the pencil-point from the zero-depth-line, the latter distance being the product derived from the distance of the point in the landscape from the base-line 15 and the scale of reduction of the copy.

The annexed drawing represents a plan view of an apparatus for producing contour-lines (a stereo-isohypsograph).

The double microscope a is the usual 20 binocular one and is fitted with a mark in each image-field. It is carried by a fixed standard a^1 , the height-slide A carrying the breadth-slide B and the depth-slide C , on which latter slides the two photograms e are 25 mounted. Studs m and n are attached to small slides m^0 and n^0 , which carry transverse slideways m^1 and n^1 . In these slideways B and C are guided by means of pins. The studs m and n engage slots i^1 and k^1 in 30 the shorter arms of levers i and k , which are pivoted at i^0 and k^0 . These levers, by means of slots in their longer arms, engage studs o and p respectively on the breadth-slide B^1 , which is carried by the depth-slide C^1 . A 35 bell-crank q^0 engages the stud t of the slide A , and a rod q^1 and a lever q serve for coupling the slide A with the slides A^1 and C^1 . The dimensions of the members q^0 and q are so chosen that the arrangement is equivalent 40 to one, in which the shorter arm of the lever q engages the stud t directly.

The three levers q , i and k have in their zero-positions, in which they are parallel to the zero-breadth-line B^0 , equal operative 45 arm-lengths l and h , the former length being the focal length of the objectives used in taking the photograms e . The breadth-slide B^1 is fitted with the pencil f^0 . At a distance h from the point of the said pencil the 50 zero-depth-line C^0 is located. The surface that can be covered by this pencil is indicated on the drawing board d^2 by dotted lines. The slide A^1 is fixed, by means of a set-screw w , in its zero-position, as the 55 tour-line to be traced belongs to the same horizontal plane, in which the axes of the objectives were located, when the photograms were being taken. The slide B^1 is likewise shown in its zero-position, in which

the pencil-point lies in the zero-breadth-line 60 B^0 . A displacement of B^1 causes a joint shifting of B and C without a change in the distance between these two. Such a change only results from a displacement of C^1 , because the distance $o\ p$ is shorter by a certain amount than the distance $i^0\ k^0$, viz. by the product derived from the base-line used when taking the photograms and the scale of the map. In order to be able to change the length of the said base-line or the said 70 scale or both, the stud p for the lever k is not fitted directly to the breadth-slide B^1 , but to an intermediate slide p^0 having a clamping-screw w^0 .

The breadth-slide B^1 is displaced by 75 means of a screw-spindle x and the depth-slide C^1 by means of two screw-spindles y . The spindle x receives its motion from a shaft x^1 by means of a bevel-wheel x^0 and of another bevel-wheel x^2 , the latter being mounted so as to slide longitudinally on the said shaft. By means of a chain-drive x^3 the shaft x^1 is coupled with the driving shaft proper x^4 , which is accessible to the right hand of the copyist. The spindles y are 80 coupled by means of their bevel-wheels y^1 and y^2 and a shaft y^3 with bevel-wheels y^4 and y^5 . The left-hand spindle is connected by a chain-drive y^6 with the driving shaft 85 y^7 , which lies to the left of the copyist. 90

I claim:

1. An apparatus for reproducing from a stereoscopic pair of photograms of a landscape a map of this landscape, comprising a 95 stereo-comparator, a drawing device, means for positively coupling the stereo-comparator and said device together and a system of actuating devices controlling the said stereo-comparator and drawing device, the said system being accessible to the operator 100 while the latter is looking into the stereo-comparator.

2. The combination of a stereo-comparator comprising three interdependent slides, a drawing device also comprising three interdependent slides A^1 , B^1 and C^1 , of which A^1 and B^1 are carried by C^1 , means for positively coupling the slides of the said stereo-comparator with those of the said drawing device and a system of actuating devices 105 controlling the said stereo-comparator and the said drawing device, the said system being accessible to the operator, while the latter is looking into the stereo-comparator. 110
